BARBECUE OVEN

George J. Janssen, Valley Park, Mo.

Application May 10, 1954, Serial No. 30,395

Term of patent 3½ years

(Cl. D81—10)

FIG. 1

FIG. 2

FIG. 3

To all whom it may concern:

Be it known that I, George J. Janssen, a citizen of the United States, residing at the city of Valley Park, county of St. Louis, State of Missouri, have invented a new, original, and ornamental Design for a Barbecue Oven, of which the following is a specification, reference being made to the accompanying drawing forming a part thereof, in which:

I claim:

The ornamental design for a barbecue oven, substantially as shown.
